ATTORNEY

UNITED STATES PATENT OFFICE.

GEORGE B. SMALL, OF TULSA, OKLAHOMA, ASSIGNOR OF THREE-FOURTHS TO TIDAL OIL COMPANY, OF TULSA, OKLAHOMA, A CORPORATION OF OKLAHOMA.

PNEUMATIC PUMPING APPARATUS.

Application filed October 28, 1927. Serial No. 229,414.

My invention relates to pneumatic pumping apparatus, and more particularly to apparatus of that character for use in connection with oil wells of such limited yield as to require only occasional pumping, the principal object of the invention being to eliminate necessity for mechanical operation and personal supervision in recovery of the oil by supplying fluid pressure medium to the well for displacing the accumulated oil at intervals determined by rapidity of the yield; the present application being a continuation in part of my application filed May 23, 1927, Serial No. 193,417.

In accomplishing this and other objects of my invention I have provided improved details of structure, the preferred forms of which are illustrated in the accompanying drawings, wherein:

Fig. 1 is a side elevation of apparatus embodying my invention, illustrated in connection with an oil well, the valve mechanism and well being in central section, with the valve closed to shut off major flow of fluid pressure medium and permit accumulation of liquid in the well.

Fig. 2 is a similar view of the same parts, showing the valve open to permit major flow of pressure medium for displacing liquid from the well.

Fig. 3 is a similar view of the same parts in position for shutting off the major flow of pressure medium.

Fig. 4 is an enlarged central vertical section of the major flow control valve.

Fig. 5 is a similar view of the flow equalizer valve.

Fig. 6 is a similar view of the minor flow bleeding valve.

Referring more in detail to the drawings:

1 designates a well hole terminating in the usual shot hole 2, and 3 a well casing comprising a shoe 4 seated on cap rock 5 above the oil sand 6, in accordance with common practice. The casing 3 is capped by a head 7 to seal the casing and retain the artificial fluid pressure medium therein. Extending through the head 7 is tubing 8, terminating at its lower end in the shot hole 50 in a perforated section 9 and leading from the top of the well to a suitable storage receptacle or pipe line (not shown).

10 designates a valve housing, preferably formed in three sections 11, 12 and 13, with top and bottom cap plates 14 and 15, attached

to the housing section by cap screws 16, 17 and 18 as shown.

Within the lower housing section 11 is a valve chamber 19, having a seat 20 and port 21, the seat and port formed in a diaphragm 22 having an upwardly facing seat 23 for the valve head 24 of a piston 25 mounted in a piston chamber 26 which communicates with the upper portion of the valve chamber 19 through the port 21. The piston 25 is provided with an annular groove 27 for facilitating bleeding of the major flow of pressure medium through a port 28 in said housing, as will presently be described.

Connected with the piston 25 by a rod 29 and located within the lower portion of the valve chamber 19 is a valve 30 adapted to rest on the seat 20 to close the port 21 and having a guide collar 31 operable in the port 21 when the valve is moving to and from its seat. The valve is normally yieldingly urged to its seat by a spring 32 which rests on the cap plate 15 and bears against the bottom of the valve 30 about a guide pin 33 on the lower face of the valve.

The piston 25 and valve 30 are cylindrical and of differential diameter, the face of the piston having a greater surface area than that of the valve 30 and also greater than that of the valve head 24 on its inner end, for a purpose presently described. The piston 25 is illustrated conventionally but may be of a type to retain a sufficient amount of air in the chamber 26 to resist closing of the valve 30 during the major flow period.

Leading to the lower portion of the valve chamber 19 through the plate 15 is a pipe 34 for supplying a major flow of pressure medium to the valve chamber from a compressor or other source of supply indicated by a portion of a cylinder C. Opening to the port 21 is a lateral port 35 terminating in a socket 36, and threaded into said socket is a conduit 37 leading to the casing head and opening therethrough for delivery of a major flow of fluid pressure medium into the top of the well casing. An orifice plate, indicated by the flanges 38, is interposed in the line 37 for producing a differential pressure on opposite sides of the equalizer valve hereinafter described.

Opening from the lower portion of the valve chamber 19 is a by-pass channel 39, terminating in a valve chamber 40, having the seat 41 and a bore 42 leading to an up-

per piston chamber 43, and communicating through a bore 44 with the piston chamber 26 so that when the by-pass is open, fluid pressure medium may pass from the primary 5 valve chamber 19 about the valve 30 into the top of the piston chamber to actuate the piston and unseat the valve against the tension of its spring 32 and the force of the pressure medium delivered through pipe 34.

10 Located within the valve chamber 40 is a valve 45 having a rod 46 extending through the bore 42 into the piston chamber 43. Mounted on the rod 46 within the chamber 43 is a piston 47, and seating on the bottom 15 of the chamber 43 and bearing against said piston is a spring 48 which normally yieldingly retains the piston 47 at the upper limit of its movement to seat the valve 45 and prevent flow of pressure medium from the 20 primary valve chamber to the piston chamber 26.

Leading from the supply line 34 around the housing to a port 49 opening to the piston chamber 43 above the piston 47, is a by-pass pipe 50, valved at 51 to restrict flow of pressure medium from the major supply to the piston chamber 43. Leading from the upper portion of the piston chamber 43 is a line 52 which extends through the casing 30 head 7 and through the casing to near the bottom of the well, where it has unrestricted outlet. The line 52 is provided with a back-check valve 53 to prevent outlet of pressure medium from the well through this line, and 35 is also provided with a bleeding valve operable as presently described, for effecting a quick return of valve 45 to its seat immediately upon opening of the major flow of pressure medium to the well.

40 Opening from the lower portion of the piston chamber 43 is a port 54, and threaded into said port is a line 55 leading through a four-way union 56 to a line 57 opening through the casing head 7 and terminating 45 in an open end within the upper portion of the well casing.

With the parts heretofore described, a minor flow of pressure medium is conducted from the supply pipe 34 around the valve housing to the upper portion of the piston chamber 43, through said chamber into the line 52, through the check valve 53 and the bleeding valve chamber and on through the line 52 to near the bottom of the well, the 55 minor flow escaping into the well being relieved through the line 37, throat 21 and vent 28 to atmosphere. Under these conditions the valve 45 is held closed by the spring 48 and there is no major flow of pressure medium to the well through line 37, the valve 30 being seated by the spring 32 and by force of pressure medium delivered through the line 34.

5 Located adjacent the primary piston chamber 26 and communicating therewith

through a port 58 is a valve chamber 59, having a seat 60 and port 61, the port communicating with atmosphere through a channel 62 leading through the valve housing. The valve 63 has a stem 64 extending into a piston chamber 65 and there provided with a piston 66 which is yieldingly urged to its upward limit of movement by a spring 67, surrounding the rod 64, seating on the floor of the piston chamber and bearing 75 against the under face of the piston. Opening from the lower portion of the piston chamber 65 is a port 68 and threaded into said port and leading to the four-way union 56 is a line 69, through which pressure medium released from the well through the line 57 is delivered to the bottom of the piston chamber 65 to balance pressure in the upper portion of the chamber under the conditions presently described.

80 Located adjacent the housing 10 is a valve housing 70 comprising the valve and piston chambers 71 and 72, closed by the sealing caps 73 and 74, the valve chamber 71 having a seat 75 and port 76, the port communicating with a channel 77 within the housing 70.

85 Threaded into the channel 77 is a line 78, leading to a channel 79 in the housing 10 through which the line communicates with the upper portion of the piston chamber 65. Leading from the line 37 at the high pressure side of the orifice plate 38 is a line 80, opening to a channel 81 in the valve housing 70 which communicates with the valve chamber 71. Located within the chamber 71 is a valve 82 yieldingly held to the seat 75 by a spring 83 that seats on the plate 73 forming part of the valve housing. The valve 82 has a stem 84 extending through the valve housing into the piston chamber 72 where it carries a piston 85 of greater surface area than the valve 82 so that when equal pressure is applied to the piston and the valve, the valve will be unseated. Opening through the cap 74 to the piston chamber 72 is a line 86 leading to the four-way union 56, and whereby pressure medium released from the well is delivered through line 86 to the piston chamber 72.

110 The bleeding valve in the minor flow line includes a housing 87 having chambers 88 and 89 at its upper and lower ends sealed by plates 90 and 91 and separated by a diaphragm 92. Centrally located within the diaphragm is a port 93 and leading from said port through the diaphragm to the exterior of the housing is an open channel 94. Surrounding the port is an upwardly facing valve seat 95. Extending through the part of the diaphragm below the channel 94, concentrically with the port 93, is an opening 96, and slidably in the opening 96 is a combination piston rod and valve stem 97. Located within the chamber 89 in the lower

end of the housing and fixed on the lower end of the rod 97 is a piston 98 adapted for reciprocation in the chamber 89. Located within the chamber 88 in the upper 5 end of the housing and fixed on the upper end of the rod 97 is a valve 99 adapted for reciprocation in the chamber 88 to open and close the port 93. The housing 87 is interposed in the line 52, the spaced ends of the 10 line being threaded into openings 100 and 101 at opposite sides of the housing and communicating with the chamber 88, so that when the valve 99 is closed (Figs. 1 and 3) 15 fluid pressure medium may pass through the chamber 88 during its flow through the line 52.

102 designates a branch leading from the major flow line 37 at a point between the main housing 10 and orifice valve 38 and 20 threaded into an opening 103 in bottom plate 91 of the bleeding valve housing 87 for delivery of pressure medium from the major flow line into the chamber 89 below the piston 98.

25 The rod 97 is of a length to provide movement of the piston 98 and valve 99 in their respective chambers and the parts are of sufficient weight to seat the valve by gravity when the piston is unrestrained by pressure 30 medium in the chamber 89.

With the parts constructed and assembled as described, the apparatus may be operated as follows:

Assuming that the liquid in the well is at 35 a low level, as illustrated in Fig. 1, major flow of pressure medium is shut off at the primary valve 30, a minor flow of the pressure medium passing from the supply line 34 to the upper portion of the piston chamber 40 43 and thence through the line 52 to the lower portion of the well, the valve 99 being closed by pressure in the chamber 88. This 45 minor flow of pressure medium is released from the well through the major flow line 37, port 21 and vent 28 to atmosphere, so that the spring 48, assisted by pressure of air in chamber 40 against valve 45 retains the piston 47 at the upper limit of its movement and the valve 45, controlling the bypass 39, on its seat, preventing escape of 50 fluid medium from the valve chamber 19 into the piston chamber 26.

The parts remain in the balanced condition above described while liquid is accumulating in the bottom of the well to a level 55 which will submerge the lower end of the line 52 and liquid seal the line. When this submergence occurs, pressure medium flowing through the by-pass pipe 50 accumulates 60 in the upper portion of the piston chamber 43 until it overcomes pressure on the valve 45 and the tension of the spring 48. The piston 47 is then forced downwardly in the chamber 43, forcing the valve 45 from its 65 seat and opening the by-pass 39 to the pri-

mary piston chamber. Pressure in the line 50-52 is relatively low (about three pounds) because of the restriction in line 50, and pressure in the chamber 40 relatively high (one hundred fifty pounds or over) because of 70 direct connection between the chamber and major flow line, but the valve 45 is opened against high pressure because of the differential areas of the piston 47 and valve 45. Flow of pressure medium through the bypass onto the piston of the primary valve, 75 lowers the piston and unseats the primary valve due to differential areas of the valve and piston. A major flow of pressure medium then passes through the line 37, and 80 orifice plate 38 and through the casing head into the top of the well in sufficient volume to displace liquid in the well and force it cut through the tubing 8. Until the major flow line has been opened by unseating of 85 valve 30, pressure in the line 52 retains the valve 99 closed.

During the displacement of the liquid by the major flow and while the minor flow line is sealed, some of the major flow will be 90 released from the well through the line 57 into the piston chambers 65 and 72 as well as into chamber 43. This flow of fluid pressure medium only serves, however, to supplement action of the spring 67 in retaining 95 the piston 66 at the upper limit of its travel, and the valve 63 closed, and pressure from the flow into the piston chamber 72 is resisted by pressure of the flow through line 100 80 from the line 37 at the high pressure side of the orifice plate 38, until the return pressure builds up in chamber 72 sufficiently to open the valve 82 against pressure from the major flow and tension of the spring 83 because of differential area of the piston 105 85 and valve 82.

Immediately upon opening of the valve 30 pressure medium is passed from the high pressure side of the orifice valve 38 in the major line 37 to the chamber 89 in the 110 housing 87 lifting the valve 99 against the relatively low pressure in line 52 and relieving the line 52, unbalancing the piston 47 so that the piston is lifted by force of the pressure medium against the valve 45 supplemented by lifting force of the spring 48 and by pressure of the medium passed from the well through line 57, union 56 and line 55 to the lower portion of chamber 43. The valve 45 is thereby closed, shutting off supply of pressure medium to the major piston chamber 26 through the by-pass 39. The major piston is, however, retained in open position and the valve 30 unseated by pressure medium trapped in the chamber 26, 125 and pressure medium continues to flow into the well through line 37 for displacing the well fluid.

During the displacement operation pressure medium supplied to the well in major 130

flow escapes through the line 57, the four-way union 56 and pipe 86 into chamber 72 and unseats the valve 82 because of the differential in area between the piston 85 and 5 the valve 82, and pressure medium from the line 80 passes through the line 78 to the top of the chamber 65. While the pressure in the top of chamber 65 is greater than that below the piston 66, it is not sufficient to 10 overcome tension of the spring 67 and the valve 63 remains closed. When the fluid has been displaced from the well, the displacing pressure medium escapes from the well through tubing 8, releasing pressure in the 15 line 57 so that it drops below that in the line 37 back of the orifice valve 38, and the higher pressure in the line 37, 80 and 78 forces the piston 66 downwardly to open the valve 63 and relieve piston 25 so that valve 20 30 may close. Major flow of the pressure medium to the well is thereby cut off at the valve 30.

When the valve 30 is closed the major flow line is relieved through the vent 28 and 25 the bleeding valve 99 in the minor flow line returns to its seat, thereby conditioning the apparatus for a succeeding operation.

While filling of the well to a level for submerging the minor flow line may require 30 considerable time, dependent on volume of yield of the well, discharge under pressure of the major flow of pressure-medium is relatively quite rapid; consequently the normal condition of the apparatus is that wherein 35 the major valve 30 is closed.

It is apparent therefore that I have provided an apparatus for pumping wells pneumatically which is automatic in its operation in response to variation of level of 40 liquid in the well, so that the displacing fluid medium is admitted to the well only when there is a sufficient accumulation of fluid in the well and that such control is effected without working parts in the well and irrespective of the time required for accumulation 45 of the fluid.

What I claim and desire to secure by Letters Patent is:

1. Pneumatic pumping apparatus including in combination with a well having a discharge line and a source of supply of fluid pressure medium, a major flow line leading from the source of pressure medium supply to the well, means including a valve and 50 an operating piston controlling flow through the major flow line, a minor flow line leading from the source of pressure medium supply to the well having interrupted flow at one side of said piston, a return line 55 leading from the well to the other side of said piston, means responsive to change in pressures in the major flow and return lines for relieving the piston, a valve housing including a valve chamber interposed in the 60 minor flow line and having an outlet to at 65

mosphere, and containing a piston chamber, a valve in the valve chamber, a piston in the piston chamber connected with the valve, and a branch on the major flow line leading to said piston chamber to provide control of 70 the last-named valve by variation in pressure in the major and minor flow lines.

2. Pneumatic pumping apparatus comprising in combination with a well having a discharge line and a source of supply of fluid 75 pressure medium, a primary conduit for supplying a main volume of fluid medium to the well, a secondary conduit for constantly supplying a limited volume of fluid medium to the well and arranged to be sealed by 80 liquid rising in the well, a valve controlling flow through the primary conduit, a valve mechanism controlling operation of said valve, and means for returning fluid medium from the well for cooperation with fluid 85 medium in the secondary conduit for normally balancing said valve mechanism, the valve mechanism being operable to effect opening of said valve by excessive pressure in the secondary conduit induced by submergence of the secondary conduit in liquid 90 rising in the well, and means for effecting closure of the valve.

3. Pneumatic pumping apparatus comprising in combination with a well having a 95 discharge line and a source of supply of fluid pressure medium, a primary conduit for conducting fluid pressure medium to the well and including a valve chamber, a valve in said chamber normally closing 100 said conduit, a piston operatively connected with the valve, separate valves controlling supply of fluid pressure medium to the piston and relief of fluid pressure medium from the piston, a secondary conduit for conducting limited supply of fluid pressure medium to the well and arranged for submergence by liquid rising in the well and including a piston chamber, a piston in said chamber connected with 105 said supply valve, means for returning fluid pressure medium from the well to said piston chamber to normally balance the supply 110 piston, means urging the supply valve to closed position and yieldable under pressure of fluid pressure medium trapped in said chamber by liquid rising in the well, and means controlled by variation in pressure in the well controlling the relief valve.

4. Pneumatic pumping apparatus comprising in combination with a well having a discharge line and a source of supply of fluid pressure medium, a primary conduit for conducting fluid pressure medium to the well, including a valve housing containing 120 valve and piston chambers and a by-pass between said chambers including a valve chamber, a valve in the primary valve chamber and a piston in the piston chamber connected with said valve, yielding means nor- 125 130

1. mally seating the valve to stop flow through the conduit, a secondary conduit for supplying fluid pressure medium to the well including a piston chamber, a valve in the by-pass chamber, a piston in the secondary conduit chamber operatively connected with the by-pass valve, means for returning fluid pressure medium from the well to the secondary conduit chamber to normally balance said piston, yielding means normally urging the by-pass valve to close the by-pass and yieldable under excessive pressure induced in the secondary conduit by sealing of said conduit by liquid rising in the well 10 to admit fluid pressure medium to the primary valve piston chamber, and valve mechanism controlled by variation in pressure in the well for relieving the primary valve piston to permit said valve to close.
2. 5. In pneumatic pumping apparatus, a valve mechanism comprising in combination with a well having a discharge line and a source of supply of fluid pressure medium connected primary valve and piston chambers, a by-pass connecting said chambers and including a valve chamber, an outlet port for the piston chamber including a valve chamber and by-pass and relief piston chambers, a valve in the primary valve chamber, a piston in the primary piston chamber connected with said valve, means normally yieldingly seating the valve, a primary conduit having sections communicating with the primary valve chamber at opposite sides of said valve for supplying fluid pressure medium to the well, pistons in said by-pass and relief piston chamber, valves in said by-pass and relief valve chambers connected with corresponding pistons, means normally 30 yieldingly seating said valves, a secondary conduit for by-passing fluid pressure medium from the supply section of the primary conduit through the outer end of the by-pass piston chamber to the well and arranged for submergence by liquid rising in the well, means connecting the well section of the primary conduit with the outer end of the outlet port piston chamber, a piston valve controlling flow through said connecting means, and means for returning fluid pressure medium from the well to the opposite ends of the by-pass and outlet port piston valve chambers to normally balance the pistons, and to operate relation with 40 said connecting valve piston to shift said connecting valve.
3. 6. In combination with a well having a discharge line, a source of supply of fluid pressure medium, a conduit leading from said source of supply to the well, a valve normally closing said conduit, a secondary conduit leading to the well, a line for supplying pressure medium for opening the valve, a valve in said line responsive to rise in pressure in the secondary conduit to open the line, and a valve in said secondary conduit responsive to pressure in the supply conduit for relieving the secondary conduit to permit the line valve to close, and means for enabling closure of the conduit valve.
4. 7. In combination with a well having a discharge line and a source of supply of fluid pressure medium, major and minor flow lines connected with said source of supply and having separate open communication with the well, with the outlet of the minor flow line below that of the major flow line, means normally restraining flow through the major flow line, and means responsive to variation in pressure in the minor flow line controlling said restraining means.
5. 8. In combination with a well having a discharge line and a source of supply of fluid pressure medium, major and minor flow lines connected with said source of supply and having separate open communication with the well, with the outlet of the minor flow line below that of the major flow line, means normally restraining flow through the major flow line, and means responsive to rise in pressure in the minor flow line induced by sealing of said minor flow line by liquid in the well controlling said restraining means.
6. 9. In combination with a well having a discharge line and a source of supply of fluid pressure medium, primary piston and valve chambers, a high pressure line leading from the source of supply through the primary valve chamber to the well, connected primary piston and valve members respectively located in said chambers, a by-pass leading from the high pressure line to the primary piston chamber, a low pressure line leading from said source of supply to the well, connected secondary piston and valve members having chambers interposed in the low pressure line and by-pass respectively, responsive to variation in pressure in the low pressure line for controlling flow through said by-pass, a return line for conducting pressure medium from the well to the secondary piston chamber for balancing pressure on the secondary piston, means 100 yieldingly urging the secondary piston to close the secondary valve, and means for enabling closure of the primary valve.
7. 10. In combination with a well having a discharge line and a source of supply of fluid pressure medium, a high pressure line leading from the source of supply to the well, connected primary piston and valve members for controlling flow through the high pressure line, the piston member movable in a chamber provided with inlet and vent ports, means for supplying high pressure medium to said chamber through the inlet port, a low pressure line leading from the source of supply to the well, a valve

for said inlet port responsive to difference in pressure in the high and low pressure lines, a return line from the well, and a valve responsive to difference in pressures in the high pressure and return lines controlling said vent port.

11. In combination with a well having a discharge line and a source of supply of fluid pressure medium, a high pressure line leading from the source of supply to the well, connected primary piston and valve members for controlling flow through the high pressure line, the piston member movable in a chamber provided with inlet and vent ports, means for supplying high pressure medium to said chamber through the inlet port, a low pressure line leading from the source of supply to the well, a valve for said inlet port responsive to difference in pressures in the high and low pressure lines, a return line from the well, and a valve responsive to differential in pressures in the return and high pressure lines controlling said vent port.
- 10
- 15
- 20

25 12. In combination with a well having a discharge line and a source of supply of fluid pressure medium, a high pressure line leading from the source of supply to the well, means including a primary piston valve
30 and piston and valve chambers controlling flow through the high pressure line, a bypass for conducting high pressure medium to the piston chamber, a low pressure line leading from the source of supply to the
35 well, valve mechanism responsive to difference in pressures in the high and low pressure lines controlling flow through the bypass, a vent for the primary piston chamber, means including a piston valve and piston
40 and valve chambers controlling said vent, a return line from the well opening to the vent piston chamber below the piston to normally retain the vent valve closed, a branch leading from the high pressure line
45 to the opposite side of the vent piston chamber, and differential area valve mechanism responsive to difference in pressures in the high pressure and return lines controlling disposition of pressure medium in the vent
50 piston chamber.

13. In combination with a well having a discharge line and a source of supply of fluid pressure medium, a high pressure line leading from the source of supply to the well, 55 means including a primary piston valve and piston and valve chambers controlling flow through the high pressure line, a by-pass for conducting high pressure medium to the piston chamber, a low pressure line leading 60 from the source of supply to the well, valve mechanism responsive to difference in pressures in the high and low pressure lines controlling flow through the by-pass, a vent for the primary piston chamber, means includ-

ing a piston valve and piston and valve 65
chambers controlling said vent, a return line
from the well opening to the vent piston
chamber below the piston to normally re-
tain the vent valve closed, a branch leading
from the high pressure line to the opposite 70
side of the vent piston chamber, and valve
mechanism responsive to accumulation of
pressure in the return line for shifting the
valve mechanism to open the branch line.

14. In combination with a well having a discharge line and a source of supply of fluid pressure medium, a high pressure line leading from the source of supply to the well, means including a primary piston valve and piston and valve chambers controlling flow through the high pressure line, a by-pass for conducting high pressure medium to the piston chamber, a low pressure line leading from the source of supply to the well, valve mechanism responsive to difference in pressures in the high and low pressure lines controlling flow through the by-pass, a vent for the primary piston chamber, means including a piston valve and piston and valve chambers controlling said vent, a return line from the well opening to the vent piston chamber below the piston to normally retain the vent valve closed, a branch leading from the high pressure line to the opposite side of the vent piston chamber, and valve mechanism responsive to accumulation of pressure in the return line for shifting the valve mechanism to open the branch line and effect opening of the vent in response to drop in pressure in the return line resulting from relief of pressure in the well through said discharge line.

15. In combination with a well having a discharge line, a source of supply of fluid pressure medium having a major flow line leading to the well, pressure reducing means in said line, valve mechanism controlling flow at the high pressure side of said line, a minor flow line leading from said source of supply to the well, a line for conducting pressure medium from said source of supply to open said valve mechanism, means responsive to variation in pressure in the minor flow line controlling flow through the conducting line, and means for enabling closure of said valve mechanism. 105 110 115

16. In combination with a well having a discharge line, a source of supply of fluid pressure medium having a major flow line leading to the well, pressure reducing means in said line, valve mechanism controlling flow at the high pressure side of said line, a minor flow line leading from said source of supply to the well, a line for conducting pressure medium from said source of supply to open said valve mechanism, means responsive to variation in pressure in the minor flow line controlling flow through the conducting line, means responsive to pressure in the high

pressure side of the major flow line for bleeding the minor flow line, and means for enabling closure of the valve.

17. In combination with a well having a discharge line, a source of supply of fluid pressure medium having a major flow line leading to the well, pressure reducing means in said line, main valve mechanism controlling flow at the high pressure side of said line, a minor flow line leading from said source of supply to the well, a line for conducting pressure medium from said source of supply to open said valve mechanism, means responsive to variation in pressure in the minor flow line controlling flow through the conducting line, a vent for the minor flow line, a piston valve normally closing said vent, and a line for conducting pressure medium from the high pressure side of the major flow line to open said piston valve to permit the main valve mechanism to close.

18. In combination with a well having a discharge line, a source of supply of fluid pressure medium having a major flow line leading to the well, pressure reducing means in said line, valve mechanism controlling flow at the high pressure side of said line, a minor flow line leading from said source of supply to the well, a line for conducting pressure medium from said source of supply to open said valve mechanism, means responsive to variation in pressure in the minor flow line controlling flow through the conducting line, and means responsive to difference in pressure in the high and low sides of the major flow line controlling release of pressure on said valve mechanism to permit said valve mechanism to close.

19. In combination with a well having a discharge line, a source of supply of fluid pressure medium having a major flow line leading to the well, pressure reducing means in said line, valve mechanism controlling flow at the high pressure side of said line, a minor flow line leading from said source of supply to the well, a line for conducting pressure medium from said source of supply to open said valve mechanism, means responsive to variation in pressure in the minor flow line controlling flow through the conducting line, valve mechanism controlling relief of pressure on the major line valve mechanism, a line leading from the well to one side of the relief valve mechanism, a branch line leading from the high pressure side of the major flow line to the opposite side of the relief valve mechanism, and valve mechanism in said branch line responsive to rise in pressure in the well to open said line and admit pressure medium therefrom to the relief valve mechanism to effect closure of the primary valve mechanism.

20. In combination with a well having a discharge line, a source of supply of fluid pressure medium having a major flow line

leading to the well, pressure reducing means in said line, valve mechanism controlling flow through the high pressure side of said line, a minor flow line leading from said source of supply to the well, a line for conducting pressure medium from said source of supply to said valve mechanism, means responsive to variation in pressure in the minor flow line controlling flow through the conducting line, valve mechanism controlling relief of pressure on the major line valve mechanism, including a piston, a branch line leading from the high pressure side of the major flow line to the valve opening side of said piston, a return line leading from the well to the valve closing side of said piston, and a differential area piston valve controlling said branch line, responsive to rise in pressure in the well to open the branch line.

21. In combination with a well having a discharge line and a source of supply of fluid pressure medium, differential pressure major and minor flow lines leading from said source of supply to the well, and means responsive to change in differential of effective forces in the major and minor flow lines, induced by liquid sealing of the minor flow line, controlling flow through the major flow line, and a relief valve in said minor flow line operable in response to change in pressures in said lines.

22. In combination with a well having a discharge line and means for supplying a fluid medium under substantially constant pressure, major and minor flow lines connecting said source of supply with the well, a return line leading from the well, means responsive to change in differential of effective forces in the minor flow and return lines and the major flow line, induced by liquid sealing of the minor flow line controlling flow through the major flow line.

23. In combination with a well having a discharge line and a source of supply of fluid pressure medium, differential pressure major and minor flow lines leading from said source of supply to the well, means including a piston valve having separate piston and valve chambers, controlling flow through the major flow line, a line leading from said source of supply to the piston chamber, secondary valve mechanism responsive to change in differential of effective forces in the major and minor flow lines controlling flow through the line to the piston chamber, a return line leading from the well, a vent line leading from the piston chamber, and valve mechanism responsive to changes in pressure in the major flow and return lines controlling flow through the vent line.

24. In combination with a well having a discharge line and a source of supply of fluid pressure medium, differential pressure major and minor flow lines leading from said

source of supply to the well, means including a piston valve having separate piston and valve chambers, controlling flow through the major flow line, a line leading from said 5 source of supply to the piston chamber, secondary valve mechanism responsive to change in differential of effective forces in the major and minor flow lines controlling flow through the line to the piston chamber,

a return line leading from the well, a vent line leading from the piston chamber, and valve mechanism normally closing said vent line in response to pressure in the return line, and responsive to pressure supplied from the major flow line when the major flow line is open to open the vent line.

In testimony whereof I affix my signature.
GEORGE B. SMALL.
